UNITED STATES PATENT OFFICE.

JOHN G. WINTER, OF WACO, TEXAS.

SIGHTING-DRILL SYSTEM AND DEVICE.

Application filed May 31, 1922. Serial No. 584,812.

To all whom it may concern:

Be it known that I, JOHN G. WINTER, a citizen of the United States, and a resident of Waco, county of McLennan, and State of Texas, have invented an Improvement in Sighting-Drill Systems and Devices, of which the following is a specification.

The subject of this invention is a sighting drill system and device therefor, designed for use in instructing soldiers and others unfamiliar with the use of fire arms in the sighting of a rifle or other fire arm.

In teaching recruits the use of fire arms one of the first courses of instructions is the proper sighting of the rifle as proper sighting is essential to accuracy in aiming.

The soldier must be made familiar with the picture presented by the rifle sights and target when the eye, the rear sight, the front sight and the target are in correct alignment.

Heretofore the correct appearance of the rifle sights has been shown by means of a sighting bar, consisting of a strip of wood about 20 inches long to which are attached small pieces of tin cut to represent the front sight, the rear sight of the rifle and an auxiliary peep sight. The piece representing the rear sight is movable so that its position can be changed from time to time by the instructor to demonstrate to the soldier, looking through the peep sight, the appearance of the rear sight and front sight when the rifle is correctly and incorrectly sighted.

The sighting bar, as above described, is a crude imitation of the rifle and does not accurately show the appearance of the sights. The sighting bar does not provide means for showing the target as an essential part of the picture which is presented to the eye in aiming. The movable rear sight is not susceptible of adjustment during the process of aiming. The only purpose of the sighting bar is to take the place of printed figures showing the rifle sights in different positions relative to the eye.

In order to ascertain whether the soldier knows the appearance of the rifle sights and target when a correct sight is taken, a rifle is placed on a sand bag which is mounted on a tripod about 5 feet in height and the rifle is pointed toward a white surface about 25 feet in front of the rifle. The soldier stands some distance behind the rifle and, without touching it, looks over the sights of the rifle and directs an assistant to move a black disc

back and forth over the white surface until the disc is brought to the point at which the rifle is aimed and where its position is recorded by a dot. This operation is repeated three times. If the sighting has been uniform in each case, the black disc will be brought each time to the same point. If the sighting has not been uniform three dots in general will be made forming the "triangle of sighting."

With this method of instruction the soldier can not touch the rifle and consequently can not place his eye in correct position with reference to the rifle sights. The effort required to hold the eye steadily in line with the sights while directing the movement of the disc is very fatiguing. This fatigue causes eye strain and consequent blurring of the sights and finally results in the soldier giving direction to "mark" when the disc is not accurately in line with the sights. By reason of the very minute angles involved in accurate aiming, neither the soldier aiming the rifle nor the assistant who is moving the disc at the command of the soldier can correctly estimate either the distance or direction through which the disc must be moved. Consequently, such verbal commands as "Up and to the right a little" or "Down about half an inch" can not possibly give accurate results as they do not correctly convey to the assistant the soldier's estimate of the angular distance through which he wishes the disc to be moved.

The present invention has been devised with a view to remedying the above mentioned defective methods of instruction by providing apparatus which has, among others, the following advantages:

Instead of the sighting bar the rifle itself is used, the eye is placed in correct position and the picture presented by the rifle sights and the target is normal and correct. Relative position of the eye and rifle sights and disc may be changed during the process of aiming so that accurate adjustment is possible;

Means are provided for the soldier himself during the process of aiming to control and fix both the position of his eye and the disc, with reference to the rifle sights by which it can be ascertained whether or not he knows the appearance of the sights when a correct sight is taken;

The rifle is immovable with respect to

the disc, except during process of adjustment, so that it may be held firmly against the shoulder in the normal position of aiming and the cheek can be laid against the stock, and the eye, in correct position, can be held steadily in line with the rifle sights without fatigue;

10 Means are provided by which the soldier himself, while aiming the rifle, moves an auxiliary peep sight with his own hand and so is able to bring his eye directly and immediately to a point in line with the sights, and to hold his eye steadily at this point by fixing the auxiliary peep sight in position;

15 Means are provided by which the soldier himself, while aiming the rifle moves the disc with his own hand and so is able to bring the disc directly and immediately to the point in line with the sights;

20 Means are provided for demonstrating to the soldier the effect on a target of changes in the windage and elevation adjustments of the rifle sights and other movements and positions of the rifle in aiming.

25 The invention consists broadly in the provision of a rest for a fire arm to which the fire arm may be rigidly secured and of a target board and mirror immovable with respect to the rest; a peep sight adjustable 30 to the rear of the sights of the fire arm and a movable target or disc under the control of one sighting the fire arm.

In the following description and in the drawings I have described and illustrated 35 convenient devices for use in carrying out my system of aiming drill, though I do not thereby intend to limit myself to the use of such forms of device, as many changes will suggest themselves to those skilled in the art 40 and, I therefore limit myself only by such limitations as are indicated by the appended claims.

45 Illustrations of practical structures used in carrying out my invention are given in the accompanying drawings, wherein:

Fig. 1 is a view in side elevation of a device constructed in accordance with the principles of my invention;

50 Fig. 2 is a plan view of the same;

Fig. 3 is a rear elevation;

Fig. 4 is a perspective view of the disc and marker;

55 Fig. 5 is a detailed perspective view of the peep sight showing the same in position on a rifle;

Fig. 6 is a longitudinal section of the same;

Fig. 7 is a section on the line 7—7 of Fig. 6;

60 Fig. 8 is a plan view of a modified form of the device.

Referring to the drawings by numerals of reference;

I provide a bar or rest 10 which is shown 65 supported on legs 11, and formed with

notched portions 12 and 13 in which a rifle 14 may be placed and bound immovably in position by any suitable binding member 15.

Mounted immovable with respect to the bar is a support 16 adapted to carry an adjustable reflector 17 which is in position in front of the rifle and to be viewed from the sights thereof.

Rigidly secured to the bar in position to be easily touched by one looking over the rifle sights, and preferably at the right hand side, is a target board 18, the front face of which may be painted white or have a sheet of white material attached thereto and on the rear face of which a sheet of white material or a miniature target 19 may be secured, if desired. Straddling the target board is a forked member 20 carrying on the end of that leg which extends along the front face of the target board a bull's eye 85 or disc 21 and on the end of the other leg which extends along the rear face of the target board a marker 22 in the form of a sharp pointed brad or pencil. The marker 22 may be surrounded by a disc or sheet of material 23, if desired, to prevent the operator from viewing the target board adjacent the marker.

While the rest is shown supported on legs 11 it is to be understood that supporting legs 95 are not essential as the rest may be placed directly on the ground when desired to conduct the drill with the one receiving instruction in prone position.

In the modified form shown in Fig. 8 100 the rest 10' is positioned on the ground and rigidly secured in place and the reflector support 16' is secured on the ground in front of the rifle rest. The ground thus taking the place of the bar 10, above referred to. 105 The target board and other elements are as heretofore described.

The auxiliary peep sight is herein shown attached to the bolt handle of the rifle, though it will be understood that the same 110 may be attached to any support adjacent the rifle which will hold the sight in position to be adjusted to the rear of the rear rifle sight.

The auxiliary peep sight consists of a bar 115 or lever 22' formed with a forked and socketed end 23' adapted to clamp over the ball of the bolt handle 24 having a handle 25 by which the lever may be manually moved about the support. At a suitable point between the support and handle, a leaf 26 is secured to the lever and this leaf is provided with a peep hole 27 through which the rifle sights may be viewed while the peep sight 120 is being adjusted. The leaf 26 may be of any desired form, the only essential being that that portion in which the peep hole 27 is provided will lie in a plane substantially perpendicular to the longitudinal axis of the bore of the fire arm when the peep sight has 125 130

been adjusted to proper position in the rear of the rifle sights. The leaf should be located near the ball and socket joint giving a fair length of handle so that a considerable movement of the handle will cause only slight movement of the leaf.

Before entering into a discussion of the operation of the device, a definition of terms and my analysis of the act of aiming will 10 be given so that the description may be more readily understood.

The point of aim is the distant point at which the rifle must be aimed in order to strike the target.

15 The line of aim is the straight line from the eye to the point of aim.

The line of sight is the straight line passing through the rear sight and front sight of the rifle.

20 The point of sight is the point in front of the rifle where the line of sight intersects a distant material object.

The act of aiming consists in moving the rifle so that the line of sight is brought into 25 coincidence with the line of aim.

With apparatus used only for instruction in sighting it is more convenient from a mechanical standpoint to fix the rifle in a rest and move the line of aim into the line 30 of sight, that is, the eye and point of aim are brought into the line of sight by means respectively of a movable auxiliary peep sight and a movable disc. Consequently, the act of aiming, in the present instance consists in moving the auxiliary peep sight and the disc rather than in movement of the rifle itself.

This process of aiming consists of two successive steps as follows:

40 First: The auxiliary peep sight is moved so that the front sight is seen in the middle of the notch of the rear sight, with the top even with the top of the notch. The eye is then in the line of sight.

45 Second: The disc is then moved so that it is seen immediately above the front sight and separated from it by a fine line of sight. The point of sight (a point immediately below the disc) then coincides with the point 50 of aim, the line of sight consequently coincides with the line of aim, and the rifle is aimed.

Instruction in sighting with this sighting drill device is graduated, in general, into 55 three successive exercises as hereinafter enumerated and described but the instruction is not limited to the such three exercises.

First sighting exercise: Instruction in alignment of the eye, rear sight and front sight. The purpose of this exercise is to demonstrate to the soldier the appearance of the sights when the eye is in the line of sight. In this exercise the auxiliary peep sight only is essential. The auxiliary peep sight is moved by the instructor until the

peep hole is brought into the line of sight. The sights of the rifle will then present a correct or normal appearance for study by the soldier who may then be required to adjust the peep sight to the proper position.

70 Second sighting exercise: Instruction in alignment of the eye, rear sight, front sight and point of aim. The purpose of this exercise is to demonstrate to the soldier the appearance of the rear sight, front sight and disc when both the eye and point of aim are in the line of sight. In this exercise both the auxiliary peep sight and the target assembly are used. The auxiliary peep sight is moved by the instructor so that the eye 75 is brought into the line of sight. The auxiliary peep sight is then fixed in the line of sight. The disc is then moved into the line of sight by means of the forked member. The sights of the rifle and the line then present a correct and normal appearance for study by the soldier.

Third sighting exercise: Instruction in uniformity in sighting. The purpose of this exercise is to demonstrate to the soldier 80

that in order to take an accurate sight it is necessary to hold the eye steadily in the line of sight while he brings the point of aim to the point of sight. In this exercise the target assembly is used. The auxiliary 85 peep sight is not used. The soldier looks over the rifle sights and brings the disc to the point of aim three successive times making in general three points, called the "triangle of sighting," the size of which 90 triangle is indicative of the uniformity of sighting.

In addition to the foregoing exercises the soldier may be taught the effect, on the target, of various movements and positions 95 of the rifle, and of the rifle sights which change the relative positions of the line of aim and the line of sight, as for instance: changes in setting of the rear sight of the rifle for windage and elevation, canting of 100 the rifle, trigger squeeze, worn or bent or loose rifle sights, flinching or closing eye at moment of firing. For this purpose the miniature target 19 proportional in size to the actual target is convenient. The miniature target is so placed on the back face 110 of the target board that the center of the bull is at the point of sight as indicated by the marker. If now, for example, the setting of the rear sight be changed to adjust for windage, the disc when brought to 115 the new point of sight will be in a different position which is consequent upon, and determined by the change in the setting of the rear sight.

I claim:

1. A sighting drill device, including a rest, a rifle provided with front and rear sights rigidly secured to the rest, an adjustable peep sight mounted to be brought to 120

125

130

- position in the rear of the rear sight, an adjustable reflector positioned in front of the rifle, a target board immovable with respect to the rest and in position to be reflected in the reflector, a disc movable over the front face of the target board, a miniature target on the rear face of the target board and a marker movable in unison with the disc and over the target.
10. 2. A sighting drill device, including a rest, means for securing a rifle provided with sights rigidly to the rest, an adjustable peep sight through which the rifle sights may be viewed, a target board connected to the rest,
15. a disc movable over the front face of the target board, a marker connected to the disc and movable in unison therewith over the rear face of the target board and a reflector for reflecting rays of light from the target
20. over the rest.
3. A sighting drill device, including a rest, means for securing a rifle rigidly to the rest, a target board connected to the rest and immovable with respect thereto, a disc movable over the front face of the target board, a marker connected to the disc and movable over the rear face of the target board and in unison with the disc and a reflector for reflecting rays of light
25. from the target board over the rest.
4. A sighting drill device, including a rest, means for securing a fire arm rigidly on the rest, a movable disc under control of the operator, and means connected to the disc and movable therewith for marking relative positions of the disc.
5. A sighting drill device including a rest, means for securing a fire arm rigidly to the rest, a movable disc under control of
30. the operator, while sighting the fire arm in position to be viewed over the rest and

means for marking successive settings of the disc.

6. A sighting drill device, including a rest, means for securing a fire arm rigidly on the rest, a target board adjacent the rest and immovable with respect thereto, a disk movable over the board, and a marker movable in unison with the disk.

7. A sighting drill device, including a rest, means for securing a fire arm rigidly on the rest, an adjustable peep sight adapted to be brought to position to the rear of the sights of the fire arm, a movable disk to be viewed over the sights, and a marker movable in unison with the disk.

8. A sighting drill device, including a fire arm, equipped with front and rear sights, and an universally adjustable peep sight adapted to be brought to position to the rear of the sights.

9. A sighting drill device, including a rest, means for securing a fire arm rigidly on the rest, a target board adjacent the rest and immovable with respect thereto, a universally adjustable peep sight adapted to be brought to position to the rear of the sights of the fire arm, whereby the eye may be brought into the line of sight, and a disk movable over the target board whereby the line of sight and line of aim may be brought into coincidence.

10. A sighting drill device, including a rest, means for securing a fire arm rigidly on the rest, said fire arm equipped with front and rear sights, and universally adjustable means adapted to be brought to position to the rear of the sights whereby the eye may be positioned in the line of sight.

JOHN G. WINTER.
